(57) **CLAIM**

The ornamental design for a vehicle front fender, as shown and described.

DESCRIPTION

FIG. 1 is a left upper perspective view of a vehicle front fender showing my new design in a condition of use, an opposite side vehicle front fender being a mirror image thereof, is claimed but not shown;

FIG. 2 is a left side elevational view thereof;

FIG. 3 is a front side elevational view thereof;

FIG. 4 is a rear side elevational view thereof;

FIG. 5 top plan view thereof; and,

FIG. 6 is a bottom plan view thereof.

The dash-dot even broken lines illustrate and surround portions of the vehicle front fender that form no part of the claimed design. The dash-dot-dot broken lines depict environmental structure which forms no part of the claimed design.
